UNITED STATES PATENT OFFICE.

JAMES D. FARMER, OF ST. LOUIS, MISSOURI.

VALVE-LOCK.

1,338,912.

Specification of Letters Patent.

Patented May 4, 1920.

Application filed August 23, 1917. Serial No. 187,735.

To all whom it may concern:

Be it known that I, JAMES D. FARMER, a citizen of the United States of America, and a resident of the city of St. Louis and State of Missouri, have invented certain new and useful Improvements in Valve-Locks for Gasolene-Motors, of which the following is a specification.

The primary object of this invention is 10 to provide an improved lock for automobiles, said lock being in the form of a valve, and located at a point between the gasolene tank and the carbureter or motor, said valve or lock being operated under a combination, 15 in which the operator of the car will be the only one that will know the combination, so as to set the same in position for allowing gasolene to be fed from the gasolene tank to the motor.

Another object is to provide an improved 20 valve lock which is comprised of a series of alining parts, said parts being movable independently of one another so that they can be properly alined, when the operator has 25 been made aware of the positions to which the parts are to be moved so that a supply of gasolene may be allowed to be admitted to the carbureter of an explosive motor.

Other and further objects will appear in 30 the specification and be specifically pointed out in the appended claims, reference being had to the accompanying drawings exemplifying the invention, and in which,

Figure 1 is a fragmentary sectional view 35 of the forward portion of an automobile, showing this improved combination locking valve connected to the supply line leading from the gasolene tank to the motor.

Fig. 2 is an enlarged vertical section having 40 a portion thereof broken away, of this improved combination valve lock.

Fig. 3 is a horizontal section taken on the line III—III of Fig. 2.

Fig. 4 is a horizontal section taken on the line IV—IV of Fig. 2.

Referring to the drawings as shown in Fig. 1, this improved combination valve and lock is located in circuit with the supply pipe 2 which leads from the gasolene tank 50 3 to the carbureter 4, and leading from said carbureter to the motor 5 is a pipe 6. The supply pipe 2 is divided into sections 7 and 8, and the valve lock 1 comprises a casing 9 to which the section 7 leads, said casing 55 being closed by the bottom plate 9^a, which

is brazed into a securing position, and turnably mounted in said casing is a vertically arranged sleeve 10, said sleeve having a pair of oppositely disposed openings 11 formed in the walls thereof, said openings of said 60 sleeve adapted to aline with the pipe sections 7 and 8, respectively, there being an opening on each side of said casing 9 for communication with said sections 7 and 8 of the pipe 2.

Formed integral with the casing 9 and extending upwardly therefrom is a tubular portion 12, and held rigid with the upper end of said portion 12 is a dial plate 13, on which are formed a series of characters 70 ranging from cipher to nine. Formed on top of said plate 13 is an annular rib 14, and formed in said rib are a series of notches 15, there being a notch 15 corresponding to each of the characters formed on said plate, 75 each of said notches being radially alined with each character.

Mounted within the sleeve 10 is an intermediate sleeve 16, said sleeve having its outer wall bear against the inside wall of 80 the sleeve 10, and having a pair of oppositely disposed openings 17 formed therein which are adapted to be placed in alinement with the openings 11 of said sleeve 10, respectively.

Extending upwardly from said sleeve 10 and rigidly secured thereto, is an intermediate tubular member 18, said member 18 extending above the dial plate 13, and secured to the upper end of said sleeve is an adjustably mounted retaining finger 19, said finger extending from a collar 20 which surrounds the upper end of said tubular member 18, there being a keying portion 21 formed on said collar which engages a slot 90 22, there being a series of said slots formed on the upper end of said member 18.

Mounted within the sleeve 16 is a turnably mounted member 23, said member having its outer wall bearing against the inner wall of 100 the member 16, and extending upwardly from said member 23 and secured thereto is an extended portion 24 which is mounted in the tubular member 25 which is formed integral with the sleeve 16, said tubular member 105 25 having its upper end extending above the member 18, and removably secured to the upper end of said member 25 is a collar 26 bearing a retaining finger 27, said collar 26 being secured to the member 25 in a manner 110

similar to the collar 20 of the tubular member 18.

The member 24 which is secured to the turnably mounted member 23 extends above the upper end of the member 25, and removably secured to the extended portion thereof is a collar 28, bearing a retaining finger 29, said collar being secured to the member 24 in a manner as related relative to the 10 collars 20 and 26.

As afore related, this improved locking device is in the form of a combination valve, and is adapted to serve as a locking element in the supply pipe leading from the fuel 15 tank to the motor, in which the device when serving as a lock closes communication between the fuel tank and the motor, but can be located in any desired position providing the device is located in circuit with the fuel 20 supply, and can be located in the fuel tank if desired.

From an inspection of Figs. 2 and 3 of the drawings, it is to be noted that the passageway or opening 30 of the centrally arranged turnably mounted member 23 is in a position of alinement with the openings 17 and 11 of the sleeves 10 and 16, thereby providing a supply passageway through this 25 improved locking element, in which the fuel 30 will be allowed to be drawn from the tank 3 through the carburetor 4 to the motor 5.

For providing proper registration of the openings or passageways of the members 10, 16 and 23, respectively, the collars 20, 26 and 35 28 of said members and retaining fingers 19, 27 and 29 pertaining thereto have been set in their respective notches 15, said notches coinciding with the numerals seven, 40 one, three, in which the finger 19 is in engagement with the notch designated as seven, whereas the finger 27 is in engagement with the notch designated as one, and the finger 29 being in engagement with the notch designated as three, said numerals 45 seven, one, three indicating the combination relative to placing the passageways of the members 10, 16 and 23 in alinement so that the motor can be started.

When a vehicle equipped with this improved device is to be left standing, the operator upon engagement with one or all of the aforesaid retaining fingers and removing the position or positions of the same will destroy the combination, or in other words, 50 offset or break the alining passageway 31, thereby preventing fuel communication between the sections 7 and 8 of the supply pipe 2, thereby providing a lock against an unauthorized person trying to start the motor, 55 as the fuel supply has been cut off, and since the unauthorized person has not been made aware of the combination relative to what set of numerals are to be used, it is obvious that a perfect lock has been established relative to preventing the supply of fuel to the 60

motor, so that the same cannot be started and the vehicle stolen.

For convenience of illustration, as shown in Fig. 1, the dial plate 13 is located beneath the bottom 32 of the vehicle, there being a 70 small trap door 33 formed above said dial plate, thereby placing the dial plate and operating fingers 19, 27 and 29 in an accessible position to the operator, and incidentally in a hidden position so that an observer 75 cannot notice the combination of numbers to which the device is set when the motor is in operation. This dial, however, and operating fingers can be placed in any other desired position, for instance, on the 80 dash board, in which case it might be desirable to do away with the straight tubular connection, as indicated by numerals 18, 24 and 25, and use a flexible connection, such as universal joints or gears, all of which are 85 considered to be known quantities as regards mechanical operativeness.

Attention is called to Fig. 3 which shows the offset position of the passageway 31 relative to the center taken through the turnable members 10, 16 and 23 which makes the combination greater as against if the passageway was made through the center of all of the members, in which instance if the passageway was formed through the 95 center, the combination seven, one, three could also be made by moving the finger indicating seven of Fig. 4 to two, the finger indicating one to six, and the finger indicating three to eight, in which all of the turnable members when turned half way around would properly register, but in the instance in which the passageway 31 is offset, the retaining fingers can be placed as indicating the elected numerals only. 100

What I claim is:

1. A locking device for preventing the passage of fuel to a motor, comprising a series of incased concentrically arranged turnably mounted sleeve like members, each of said members having a pair of relatively long and narrow opposing slots extending to the bottom thereof, each pair of slots being off-set relative to the center of said members, said slots of each of said members being adapted to register with one another, and means located outside of the casing of said members for pre-determining the operative and inoperative positions of said members. 110

2. A locking element for preventing the passage of fuel to a motor, comprising a series of incased turnably mounted sleeve like members, each of said members having a pair of relatively long and narrow opposing slots extending to the bottom thereof, said slots of each of said members being adapted to register with one another and form an off-set passage relative to the center of said members. 120

3. A locking element for preventing the passage of fuel to a motor, comprising a series of incased concentrically arranged turnably mounted sleeve like members, each of said members having a pair of off-set opposing relatively long and narrow slots extending to the bottom thereof, said slots

of each of said members being adapted to register with one another, and means located outside of the casing of said members for predetermining the operative and inoperative positions of said members.

JAMES D. FARMER.
